United States Patent Office.

ROBERT S. STENTON, OF BROOKLYN, NEW YORK.

Letters Patent No. 60,801, dated January 1, 1867.

IMPROVEMENT IN WRENCHES.

The Schedule referred to in these Letters Patent and making part of the same.

TO ALL WHOM IT MAY CONCERN:

Be it known that I, ROBERT S. STENTON, of the city of Brooklyn, county of Kings, and State of New York, have invented certain new and useful improvements in Wrenches; and I do hereby declare that the following is a full and exact description thereof, reference being had to the accompanying drawings, and to the letters of reference marked thereon, similar letters of reference indicating corresponding parts.

Figure 1 is a side view of my wrench, showing the manner of grasping the hexagon nut in perspective.

Figure 2 is a similar view, showing the manner of grasping the square nut.

Figure 3 is a side view of my wrench, with a straight wooden handle.

I make my wrench of iron, cast or wrought, or of steel, or of parts of either. I construct it with the handle straight or curved; if straight it may be of wood, fig. 3. I prefer the curved iron handles, C², figs. 1 and 2. I construct the jaws A B, figs. 1, 2, and 3, of the wrench at an angle of sixty degrees from the plane of the straight shank C¹, in order to clasp the hexagon on four sides, grasping and coming in immediate parallel contact with three—the first, second, and fourth, as seen in fig. 1. The hexagon has many advantages over the square nut, not only in beauty, but in certain positions it is more easily adjusted. The screw-wrenches thus far constructed with jaws, whether perpendicular or inclined to the shank, are only adapted to grasping square nuts, and with such you can only hold the hexagon nut on two sides. This is insufficient to tighten it properly or to loosen it the same, as the case may be, without abrading the corners in such a manner as gradually to render the nut useless, and this is proved by the fact that machinists who have frequent occasion to operate upon one or more hexagon nuts, almost always make for themselves fixed wrenches, well knowing that with no wrench as yet made could they operate a finished hexagon nut without danger of injuring it. Another cause of abrasion arises from not adjusting the wrench to fit the nut properly, thus slipping, and, by repetition, gradually reducing the nuts from the angle to a circle; the first difficulty is entirely removed, and the second comparatively so.

Extending from the lower end of the shank C¹, at its junction with the handle, C², or the tang in the straight handle, fig. 3, I place the projection or screw-rest J, which is solid and in one piece, with the shank C¹ and the handle C², or the tang in the wood handle, fig. 3. This projection may be in front or at back, or on either side, according to the position of the screw. In figs. 1 and 2 it is at the back, which I prefer; in fig. 3 it is in front. The adjusting screw D, figs. 1 and 2, has its bearings at I and J, the shoulder of the journal resting against the head B and the projection J, thus supporting and giving additional strength to the head B and shank C¹. It has at its lower end a nut or rosette, or its equivalent, D, contiguous to the projection J. Though I prefer to make it so, the screw D does not necessarily require to have more than one bearing in the projection J, not extending beyond the length of the movable jaw A. In this case, however, a recess, a, fig. 3, would have to be formed in the shank C¹, fig. 3, for the nut or rosette to revolve in to keep the screw in its place. Fig. 3 shows a wood-handle wrench on this principle.

It will be observed that the jaw A is made much (about one-half) longer than the jaw B, from the plane of the straight shank C¹, so that when a square object is placed therein, the distances will be equal, or nearly so, from four to five and six to seven, as indicated by the red lines on fig. 2. Unless this was the case, if the jaws were of equal lengths, or with only a trifling elongation, a wrench of this description would be available only for hexagon nuts; it could only grasp about one-third of the square nut, and would be as inefficient on square as wrenches at present constructed are on hexagon nuts.

To enable others skilled in the art to make and use my invention, I will proceed to give a full and exact description thereof, reference being had to the accompanying drawings, and the letters of reference marked thereon.

I make my wrench of iron or of steel, cast or wrought, or of parts of either. The shank C¹, the handle C², or tang C², fig. 3, and the projection J, are cast or wrought in one piece. The jaws A and B may be cast or forged; I prefer to use cast malleable iron. They are cored out very near the size of the shank C¹, so that they will require but little work in fitting the core of the head; jaw B is smaller than the one used for the movable jaw A, as in order that the jaw B may be perfectly firm, I have recourse to every possible means to adjust it, so as to render the wrench as strong at this point as it would be if the head and bar were formed in one solid piece. In the first place the head is made hot and shrunk on, the hole at the top of the head B is countersunk, and the top of the shank C¹ is riveted to fill the countersink; it is then drilled through head and shank, and

a steel or iron pin or screw riveted in on both sides; finally, if needed, I brace them. The jaw A is cored or drilled at G H, the hole being the full size of the circumference of the screw for about one-half its length, but smaller, so as to be tapped in the other half for the screw D to rest in and to work in. The screw D I prefer to make of wrought iron or steel. Having all the parts fitted, take the screw D, give it a few turns in the movable jaw A, slip said jaw on shank C¹, letting the journal into the hole J, take the jaw B, attach the same to the shank C¹, as already set forth, or in some equally secure equivalent manner, the other journal of the screw entering the hole I; all is then together, and the wrench, when polished, is complete.

Having thus fully described my invention, I do not claim the combination of the solid projection J with a nut, rosette, or its equivalent, D, in contiguity, as that is already patented in my patent issued July 24, 1866, but what I claim and desire to secure by Letters Patent, is—

Making the inclining jaws A and B at such an angle with the straight shank C¹ as to embrace four sides, and to grasp in parallel contact three sides of a hexagon nut, in combination with a sufficient elongation of the lower jaw, so as to grasp two sides of a square nut, as set forth.

R. S. STENTON.
